UNITED STATES PATENT OFFICE.

HORACE FALK NEUMEYER, OF MACUNGIE, PENNSYLVANIA.

WASTE-VALVE FOR HYDRANTS.

SPECIFICATION forming part of Letters Patent No. 628,023, dated July 4, 1899.

Application filed December 29, 1898. Serial No. 700,639. (No model.)

To all whom it may concern:

Be it known that I, HORACE FALK NEUMEYER, a citizen of the United States, residing at Macungie, in the county of Lehigh 5 and State of Pennsylvania, have invented a new and useful Waste-Valve for Hydrants, of which the following is a specification.

My invention relates to improvements in waste-valves for hydrants and like structures; 10 and the primary object of the invention is to provide an improved construction in which the delivery-pipe is drained automatically of the water standing above the plunger-valve, thereby overcoming any tendency of the water freezing in the pipe during cold weather 15 and preventing any escape of water while tapping the pipe or main.

A further object is to provide an improved construction in which a fluid-operated piston- 20 valve tends to close the drain-port before water is permitted to pass through the hollow plunger-valve to the delivery-pipe, and said piston-valve is operated solely and automatically by the pressure of the fluid in the hydrant. 25

A further object is to construct the hollow or chambered plunger-valve with guides that serve to direct the piston-valve and form the waterways for the passage of water and for 30 the water to press the piston-valve closely against the plunger-valve for securely closing the drain-port therein.

With these ends in view the invention consists in the novel combination of elements 35 and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a vertical section of my improved waste-valve for hydrants, showing the 45 chambered plunger-valve seated in the foot-casing and with the piston-valve lowered to the seat in the chambered plunger-valve for opening the drain-port therein. Fig. 2 is a view similar to Fig. 1 with the plunger-valve 50 raised to its open position and showing the piston-valve elevated to close the drain-port in said plunger-valve. Fig. 3 is a vertical sec-

tional view through the chambered plunger-valve on a plane at right angles to Figs. 1 and 2 and indicated by the dotted line 3 3 of Fig. 2. 55 Fig. 4 is a cross-sectional view on the line 4 4 of Fig. 3. Fig. 5 is a detail perspective view of the piston-valve.

Like numerals of reference denote like and corresponding parts in each of the several figures of the drawings.

The casing 10 at the foot of the hydrant is provided with an elbow 11, to which the water-supply pipe 12 is connected by means of the coupling 13, and within this casing 10 is 65 the chamber 14 and the valve-seat 15. The outside or main pipe 16 of the hydrant has a threaded connection 17 with the valve-casing 10, and within the chamber 14 of the casing operates the plunger-valve 18, to which is connected the discharge-pipe 19 of the hydrant. 70 This discharge-pipe 19 has a threaded lower extremity 20, which is screwed into the internally-threaded coupling-neck 21 of the plunger-valve 18, and, as is usual in the art, the 75 discharge-pipe 19 is connected with a suitable operating device of the hydrant for the purpose of raising or lowering the plunger-valve 18 away from or toward its seat 15 in the foot-casing 10. As the means for operating the hydrant are ordinary in the art and constitute no part of the present invention, I have not considered it necessary to illustrate or describe the same. The plunger-valve 18 is chambered or hollow, and its upper end is 80 partially closed by the coupling-neck 21, while its lower open end has a female thread. In this lower open end of the chambered plunger-valve is screwed the upper threaded part of a plug 22, which is provided, at a point intermediate of its length, with a circumferential collar 23. A cup-shaped packing 24, of leather or any other suitable material, is slipped over the plug 22 to impinge or bear 85 against the lower edge of the plunger-valve 18, and this packing is clamped firmly in place between the collar 23 of the plug 22 and the lower edge of the plunger-valve 18 when the threaded plug is screwed home into the chambered plunger-valve. The plug 23 is bored to 90 provide the longitudinal water-passage 25, and said plug is furthermore provided with a transverse waterway 26, which opens into or 95 communicates with the longitudinal passage 100

25. The lower part of the plug 22, which is formed with the transverse waterway 26, protrudes below the plunger-valve 18, and to the lower extremity of this valve-plug 22 is fitted 5 a gasket 27, that is held firmly in place by the screw 28, which is attached to the plug 22.

The hollow plunger-valve 18 has the piston-valve chamber 29, and the lower part of this chamber is formed, as hereinafter more fully 10 described, with a series of guide ribs or flanges 30 31 32, three in number and arranged to direct the slidable movement of the piston-valve and to form a blind passage and waterways for the escape or passage of the fluid through 15 the chambered plunger-valve.

In the embodiment of the invention represented by the drawings I have shown the piston-valve chamber 29 of the plunger-valve 18 as provided with a series of three longitudinal 20 guide ribs or flanges, (indicated at 30, 31, and 32,) which are parallel to each other, and the space between the upper ends of the guide-ribs 31 32 is closed by an arc-shaped transverse partition 33, which joins with said ribs 25 31 32 for the purpose of forming a blind passage 34, as shown more clearly by Figs. 3 and 4, to which water is admitted when the piston-valve is raised for the purpose of exerting lateral pressure on the piston-valve and 30 forcing the latter closely against the wall of the plunger-valve 18, in which the drain-port is provided. It will be understood that the blind passage 34 is formed between the ribs 31 32, and that the upper end of this blind 35 passage is closed by the transverse partition 33. The space between the ribs 30 and 31 forms a waterway 35, and similarly the space between the ribs 32 and 30 forms another waterway 35, thus providing two waterways 40 on opposite sides of the blind passage 34. (See Figs. 3 and 4.) The upper part of the piston-valve chamber 29, above the upper ends of the ribs 30 to 32, inclusive, is enlarged, as at 36, and with this enlarged part of the chamber 45 29 communicates the waterways 35, thereby providing for the free upward flow or passage of the water through the chamber 29 when the plunger-valve 18 is raised from its seat and the piston-valve from its seat on the 50 upper end of the bored plug 22. The plunger-valve 18 is furthermore provided with a drain-port 37, which is formed in the valve 18 at a point diametrically opposite to the blind passage 34 and in a position to communicate with one of the guide-ribs 31, and this 55 drain-port is formed in the plunger-valve 18 at a point above the upper extremity of the seat formed by the threaded plug 22, the distance of said port 37 from the plug 22 exceeding 60 the length of the piston-valve 38. This piston-valve is made of a solid piece of metal which is turned to accurately fit the space enclosed or bounded by the ribs 30 31 32, and the length of the piston-valve is less than the distance between the threaded plug 22 and the 65 drain-port 37, thus opening or exposing the drain-port 37 when the piston-valve is lowered

to rest upon the upper extremity of said plug 22. The piston-valve is free to slide or travel in a vertical direction within the guides formed by the ribs in the chamber 29 of the plunger-valve, and the piston-valve is lifted solely by the pressure of water admitted by the bored plug 22 to the chamber of the plunger-valve, while the valve 38 is adapted to seat itself by 70 gravity when the flow of water through the hydrant is cut off. This piston-valve is provided at its upper end with a central projecting nib 40, and it is furthermore provided with a vertical vent-passage 41, that extends entirely 75 through said piston-valve and opens through the opposite ends thereof. The upward movement of the piston-valve under the pressure of the rising column of water admitted to the chamber of the plunger-valve 18 is arrested 80 by means of a stop-bar 42, which is arranged in the enlarged upper part 36 of the chamber 29 to lie directly in the path of the central nib on the piston-valve. The valve itself does not contact with the stop-bar; but its central 85 nib is arranged to engage with the stop-bar, thus providing a limited area of contact for the valve against the bar and enabling the water to flow freely around the piston-valve and thence to the plunger-valve into the discharge-pipe 19.

Although I have shown and described the chamber of the plunger-valve as provided with a series of three ribs to form a blind passage and two waterways, I do not strictly confine myself to this specific construction of the ribs for the formation of the blind passage and the two waterways, as I am aware that the piston-valve may be pressed closely against the side of the plunger-valve having the drain-port in order to securely close the latter by the pressure of water against the piston-valve by modifying the internal construction of the chambered plunger-valve.

The operation may be described as follows: 110 Assuming that the plunger-valve is lowered for the washer 27 to occupy the seat 15 in the casing 10, the flow of water through the hydrant is cut off and the piston-valve seats itself by gravity on the upper end of the plug 115 22, thereby opening the drain-port 37 and permitting the water above the plunger-valve and the piston-valve to trickle or drain through the port 37 into the outside main pipe 16 of the hydrant. When the operating device of 120 the hydrant is actuated to raise the plunger-valve 18 from its seat 15 in the casing 10, water is permitted to flow under pressure from the pipe 12 through the casing 10 into the port or waterway 26 and the passage 25 of 125 the bored plug 22. The pressure of the water against the lower end of the piston-valve 38 lifts the valve and impels it endwise in the chamber 29, the piston-valve being guided by the ribs or flanges within said chamber 29. 130 At the initial upward movement of the piston-valve under the pressure of the water the lower end of the blind passage 34 is exposed and the piston-valve traverses the drain-port

37 before the waterways 35 in the chambered plunger-valve are opened, whereby the water-pressure in the blind passage acts against the piston-valve to force it laterally into close frictional contact with the wall of the plunger-valve in which the drain-port 37 is formed, thereby closing the drain-port against the leakage of water. The continued upward movement of the piston-valve under the pressure of the water which accumulates in the chamber 29 of the plunger-valve opens or exposes the waterways 35 to permit the water to flow around the piston-valve through the waterways 35 into the enlarged part 36 of the chamber 15 and thence to the discharge-pipe, and if the pressure of water is sufficient to still further elevate the piston-valve its nib 40 impinges against the stop-bar 42 to positively arrest the upward movement of the piston-valve 20 under pressure of the water. During the vertical travel of the piston-valve it is kept closely pressed against the side of the plunger-valve having the drain-port by the pressure of the water confined within the blind passage, and thus the drain-port is closed securely by the piston-valve while the plunger-valve is open and the water is flowing through the hydrant. When the water 25 is cut off and the plunger-valve is lowered to its seat, the piston-valve is permitted to descend by gravity and to rest upon the threaded plug 22, and the descent of the piston-valve uncovers the drain-port 37 for the water in the pipe 19 to discharge through the drain-port 37, thus overcoming any tendency of the water to freeze in the hydrant and preventing any escape of water while tapping the main. 30

The outside pipe 16 of the hydrant is provided with a drain or waste port 16^a at or 40 near the lower end for the water to make its escape when drained from the hydrant.

Changes may be made in the form and proportion of some of the parts, while their essential features are retained and the spirit of 45 the invention embodied. Hence I do not desire to be limited to the precise form of all the parts as shown, reserving the right to vary therefrom.

Having thus described the invention, what 50 I claim is—

1. In a waste-valve, the combination of a chambered casing provided with waterways and with a drain-port which communicates with a piston-valve chamber within said casing and a piston-valve movable freely in said chambered casing and seated normally therein by gravity to expose the drain-port, said piston-valve being moved in an upward direction solely by the pressure of water admitted to the casing and held into close frictional contact with that side of the casing having the drain-port by pressure of the

water in one of the ways, substantially as described.

2. In a waste-valve, a chambered casing 65 provided with guide-ribs arranged to form waterways and with a drain-port which communicates with a piston-valve chamber in said casing, combined with a pressure-operated piston-valve slidably confined by the 70 guide-ribs within the casing and exposed to the pressure of water in one of the ways, to be deflected laterally by water-pressure into close frictional contact with the wall of the chambered casing having the drain-port, sub- 75 stantially as described.

3. In a waste-valve, the combination of a chambered shell provided with waterways and with a drain-port, and a pressure-operated elongated piston-valve fitted slidably 80 within the shell and arranged to close the drain-port during its upward travel, substantially as described.

4. In a waste-valve, the combination of a chambered shell provided with internal guide- 85 ribs arranged to form waterways and with a drain-port which opens through one of the guide-ribs, an elongated piston-valve slidably confined within the guide-ribs of the shell and arranged to close the drain-port 90 when lifted by the pressure of fluid, and means for limiting the upward movement of said piston-valve, substantially as described.

5. In a waste-valve, the combination of a chambered shell provided in one wall thereof 95 with a blind passage and in its opposite wall with a drain-port, combined with an elongated piston-valve slidably confined within the shell to close the drain-port during its end-wise movement, substantially as described. 100

6. In a waste-valve, the combination of a chambered plunger-valve provided with guide-ribs forming waterways and with a drain-port, a perforated plug fast with the lower end of the chambered plunger-valve, a 105 pressure-operated piston-valve slidably confined in the chamber of the plunger-valve, and a stop in the path of the piston-valve, substantially as described.

7. In a waste-valve, a chambered shell provided with internal guideways, a drain-port opening through one of said guideways, and a stop-bar above the guideways, in combination with an elongated solid piston-valve provided with a central nib and with a longitudinal drain-passage, substantially as described. 110 115

In testimony that I claim the foregoing as my own I have hereto affixed my signature in the presence of two witnesses.

HORACE FALK NEUMAYER.
